UNITED STATES PATENT OFFICE.

LESTER P. BARLOW, OF NEW HAVEN, CONNECTICUT.

RADIATOR DEVICE FOR GAS ENGINES.

Application filed October 1, 1918. Serial No. 256,444.

To all whom it may concern:

Be it known that I, LESTER P. BARLOW, a citizen of the United States, and a resident of New Haven, in the county of New Haven 5 and State of Connecticut, have invented certain new and useful Improvements in Radiator Devices for Gas Engines, of which the following is a specification.

The invention relates to an improvement 10 in radiator devices for gas engines, particularly for automobiles. It is a common experience for drivers to find their "radiators boiling" or rapidly losing water in the form of steam through the vent pipe, and 15 aside from the consequent failure in radiator function there is the inconvenience of intermittently furnishing additional water to the radiator and at times the impossibility of finding the water.

20 The object of my invention is to provide by simple devices means to prevent any excessive loss of water through the vent pipe and insure the proper functioning of the radiator even under long-continued and 25 severe engine work. I accomplish this object, broadly, by forcing the water and any mixture of water and steam from the cylinder jacket through the usual radiator without any access to the necessary vent 30 pipe in the system until the steam has had all possible opportunity to condense into water and remain in the system instead of leaving it. The ordinary radiator now used really forces the steam to pass out of the 35 vent pipe because the vent is located as if the purpose were to get rid of the water as fast as it is turned into steam. My purpose is the reverse, and the invention is found not only in the broad feature recited but in the 40 advantageous arrangement for improving the radiator function generally without radical requirements in equipment.

The invention will be described with reference to the accompanying drawings but 45 without any intention to limit the scope of the claims by the detailed description, such scope depending upon the prior art as applied to this as a required disclosure.

In the drawings,—

50 Fig. 1 is a sufficient detail view of my invention as applied to radiators of present construction without change except to plug the vent pipe of such radiators; and

55 Fig. 2 is a sufficient detail view of a radiator having my invention in a modified form built therein.

Referring to Fig. 1, a catalogue identification of well-known parts follows: R is the usual radiator, but its vent pipe and filling opening are "plugged" against acting as an 60 outlet for the water and steam; H is the hot water inlet to the radiator from the cylinder jacket E; C is the outlet; and F is the fan.

The outlet C connects with the bottom of 65 the tank T for my purpose. Water pump P connects the bottom of the tank T by pump inlet I (preferably at the middle to insure water supply) and the cylinder jacket E by pump outlet O. A vent V leads from the 70 top of the far side of tank T to any suitable point.

Tank T has a capacity when about half full to keep the cooling system in normal running condition with the pump working. 75 When the pump stops, radiator R may drain into tank T to about fill it.

The operation will now be described. The pump circulates the water through the system in the usual manner and with the usual 80 effects until such time as there is a tendency for the engine to overheat, which would ordinarily result in the loss of water and an increase in such tendency. According to my invention, the mixture of steam and hot 85 water forced into the radiator has no place to go except through the water passages of the air cooling section. The ordinary vent outlets having been plugged, the only possible outlet, then, is through the cooling section and from the bottom of the radiator to the bottom of the tank. The small amount of steam mixed with the water through this course to the tank will be condensed, in part 90 at least, and any remaining in the mixture 95 will enter the volume of water in the tank and must pass in contact with it to and along the top of the tank where the water is splashing around before it can reach the vent. If by this time it has not condensed, 100 it may pass off to the atmosphere, for it has been held for condensing effect in the system as long as feasible.

With the structure just described the addition to what is now in common use is the 105 tank T between the radiator and the pump and the relocation of the vent pipe, with the result that the water stays in the system and more effectively maintains the desired temperature around the cylinders, particularly 110 when the engine is working hard and long, as it must do in truck practice.

In Fig. 2 is a modified construction, from which I accomplish my broad objects and additional features of improvement. The outside shell 1 of the radiator is of usual construction, although it may be of improved design because the cross-air and water passages or ordinary air-cooling section need not be so large for equal cooling effect in my construction, thereby permitting a wider scope for variation in shell design.

A bottom collecting chamber 7 is formed in the shell by horizontal wall 4 extending above the shell bottom between the front wall 3 and a like back wall (not shown). The shell side wall is indicated as an inverted U-shape, and a like wall 2 extends from wall 4, and between front and rear walls in spaced relation to the side walls to form the inverted U-shaped passage 6. This passage communicates with the ordinary filling opening F of a radiator and from which opening a small open-ended vent pipe V extends to a convenient drip point P outside the radiator.

The radiating section proper indicated by R of any desired form (as, for example, the Mayo-honeycomb type) is held by usual construction between the side walls 2 and the boundary walls H which show the outside line of such section extending between the front and rear faces of the radiator.

In this construction a distributing chamber T is formed between the wall 2 and the upper face of the cooling section which is closed except for the hot water inlet I from the cylinder jackets and the water passages through the cooling section R. The collecting chamber 7 is connected to the bottom of these water passages and at each side this chamber has a passage 5 connecting with the water passage 6.

The operation of this form will now be described. The system is filled with water through F. The water passes down through passage 6, through opening 5, fills collecting chamber 7, passes out through outlet O to fill the system including the cylinder jackets (not shown), rises in the water passages of radiator R and fills them as well as water chamber T and the pipe connection with inlet I. Meanwhile, the water has filled passages 6 until when water reaches the vent opening in V the system is full.

The radiator R works in a normal manner with the water from inlet I, in distributing chamber T, passing through water passages of R to collecting chamber 7 and out through outlet O. The water in passage 6 is an extra supply for my purpose.

If the engine heats the water and forms steam, it collects in chamber T. The steam pressure forces the water out of radiator R and up passages 6 and out vent V in proportion to the pressure. The steam then

enters the water passages of radiator R and the latter acts in part as a steam condenser. If steam continues to accumulate, all the water is forced out of R until the steam collected in chamber 7 passes through openings 5 and up through the water in passages 6 to be, in part at least, condensed. The radiator R is now acting as a steam condenser and the columns of water in passages 6 assist in the condensation of the steam, while the water is collected in chamber 7 for outlet O and vent V safeguards the system. The operation just described is, of course, an extreme case, and at the first let-down of the pressure the water in passages 6 under a sufficient head, due to the relative arrangement of these passages, returns or forces water to fill the radiator system properly and automatically.

Some water has left through vent V in the described operation, but this amount was an excess supply and the water in passages 6 still forms an emergency supply for the substantial function in a repeated operation. Thus, upon the second operation an increase of pressure sufficient to force the water out of radiator R into passages 6 will just about raise the water in such passages to the level of the vent tube inlet, whereupon that water will have its full condensing action on the steam rising through it.

In the modification disclosed in Fig. 2, a pet-cock should be provided at the highest point of the cooling system to allow the air to escape when the system is being filled with the cooling medium.

It is recognized that a substantial column of water cannot be supported from steam pressure below it but that the steam will rise through the water in the column. That is just what happens in my device, and as soon as the steam can work through passages 5, it rises in the columns of water in passages 6 to suddenly release the pressure. Such steam is largely condensed and the pressure of the water in the columns returns the water to the radiator, which is the action I desire.

From the described operation one can understand the function of the improved device and its general principle of operation. In actual use the exact operations will vary widely, but according to the desired principle of condensing steam, if reasonably possible, before permitting its release to the atmosphere and of providing for automatically supplying the radiator with a full volume of water as soon as reasonably possible without carrying an excessive volume of water for the purpose.

What I claim is:—

1. A cooling system for gas engines including a cooling unit, a reservoir, connections between said reservoir and said cooling unit, connections between said cooling unit

and the water jacket of a gas engine, the arrangement of said connections being such that the cooling unit operates as a condenser when the circulating medium becomes gaseous.

2. A cooling system for gas engines including a cooling unit, connections between the upper portion of said unit and the upper portion of the water jacket of an engine, connections between the lower portion of said unit and the lower portion of said water jacket, a reservoir in communication with said system, the arrangement of said

reservoir being such that steam generated in the system forces the water downwardly 15 out of said cooling unit into said reservoir.

3. A cooling system for gas engines comprising a cooling unit, said unit being normally filled with a cooling liquid, a reservoir, connections between said reservoir and cooling unit so arranged that for steam generated in the system to escape it must force out of the cooling unit the cooling liquid therein.

LESTER P. BARLOW.
